CONTAINER

Nelson Geertsen, Chicago, Ill., assignor to American Can Company, New York, N. Y., a corporation of New Jersey

Application December 31, 1940, Serial No. 372,666

6 Claims.

(CL. 221—11)

This invention relates to a dispensing container for liquids or for any freely flowing materials and has particular reference to a combination plug insert and friction plug closure member which is adaptable for insertion into an opening in a container cover and which carries and covers a hingeable pouring spout.

The invention contemplates the provision of a dripless pouring spout hingedly connected to a friction plug insert member which is seated into an end cover of a friction top container preferably adjacent to one edge so that when the spout is raised into a dispensing position controlled pouring of the container contents is possible. By way of example, table syrup, condensed milk, granular material and other similar freely flowing products are well adapted to such pouring.

An object of the invention is the provision of a sheet metal container for storing and dispensing liquids or granular substances wherein a curved wing type extensible pouring spout is hingedly connected to and arranged to be positioned within a friction plug insert located adjacent an edge of the container so that the spout may be swung into the plug insert when not in use and the unit may then be closed by a friction plug closure.

Another object of the invention is the provision of a dripless type pouring spout which is hingedly connected within a shallow drawn plug insert and which is adapted to dispense liquids, wherein any residual liquid clinging to such a spout flows back into the container, thereby keeping the top of the container free and clean of the container contents.

Another object of the invention is the provision of such a dispensing container which includes a hinge type retractable pouring spout, novel as to shape and as to its connection with a friction plug insert so that it may be easily swung into an extended position, for dispensing or may be moved back into a retracted position following a dispensing operation whereupon the entire insert member and its pouring spout may be temporarily closed and protected by an easily removable plug closure member.

Numerous other objects and advantages of the invention will be apparent as it is better understood from the following description, which, taken in connection with the accompanying drawing, discloses a preferred embodiment thereof.

Referring to the drawing:

Figure 1 is a fragmentary view in vertical section of a liquid filled dispensing container em-

bodying the invention and showing a hinged spout in inoperative position within a plug insert and also showing an auxiliary cover closed upon it;

5 Fig. 2 is a fragmentary plan view of a container with the auxiliary cover removed, and showing the pouring spout in an operative position with the pouring outlet disposed in the panel of the plug insert;

10 Fig. 3 is a fragmentary view similar to Fig. 1 taken substantially along the broken line 3—3 in Fig. 2 and showing the pouring spout in an extended position for dispensing the container contents by a pouring action;

15 Fig. 4 is a fragmentary sectional view similar to Fig. 1 and showing in elevation the plug insert member seated in the main cover with the auxiliary cover in a closed position within the plug insert;

20 Fig. 5 is a perspective view of a preferred form of pouring spout; and

25 Fig. 6 is a view similar to Fig. 5 and showing a modified form of pouring spout.

As a preferred embodiment of the invention, there is shown in the drawing a sheet metal friction plug type container comprising a cylindrical container body 11 closed at its upper end by a friction ring 12 and a main friction plug cover 13 which is seated within the ring. The friction ring 12 is secured to the container body 11 by the usual form of soldered joint 14.

30 The ring member 12 has an inwardly inclined wall 15 which terminates in a laterally and inwardly bent wall 16 and this constitutes the friction seat for the main cover member 13. This cover member has a countersunk panel wall 17 and is surrounded by an annular friction wall 18 which is outwardly curled at its marginal edge portion as at 19.

35 The panel 11 of the main cover 13 has an opening 22 (Fig. 1) disposed adjacent one edge of the cover which is surrounded by an upwardly extending friction wall 23. This wall produces a friction seat for the friction plug insert member designated by the numeral 24.

40 The friction plug insert has a panel 25 which is surrounded by a stepped annular wall 26 terminating in an outwardly rolled rim 27. The panel 25 is furnished with an elongated dispensing opening 28 (Fig. 2) disposed intermediate two struck-out tongue members 29. The tongue members 29 are narrow, rectangular in shape and are cut along three sides with a remaining narrow side joining them to the panel 25 (Figs. 1,

2 and 3). These tongue members are curled into a circular loop and provide a hinge connecting means for either a preferred or modified form of pouring spout 31, 32, the preferred spout 31 being shown in Fig. 5.

The pouring spouts 31, 32 (Figs. 5, 6) comprise curved wing-like members having an arcuate or curved wall 33 with a rounded front edge portion 34 which terminates in a flared edge as at 35. The curved wall 33 opposite the rounded edge portion 34 has a stepped arcuate or curved wall 36 which is of slightly smaller diameter than the wall 33. This stepped wall is arranged to border upon the stepped wall 26 in the plug insert 24 when the pouring spout is in an operative position.

An arcuate ridge 37 is formed on the upper surface of the panel 25 (Fig. 2) adjacent the wall 26 to produce a groove or channel as at 38. The rear edge of the wall 36 on either form of pouring spout is adapted to seat into such a groove when a spout is placed into an extended position for dispensing (Fig. 3). This eliminates the possibility of the container contents leaking past the wall edge and thence between the spout walls 33, 36 and the wall 26 of the plug insert during a dispensing operation.

The curved or cylindrical wall 36 of the pouring spout 31 (Fig. 5) has an inwardly extending rectangular trunnion-like tongue 39 disposed at each or opposite ends. This tongue serves as a pintle for connecting the spout 31 within the insert member 24 in a hingeable connection when interlocked with the looped tongue members 29.

The curved wall 36 of the pouring spout 32 (Fig. 6) has two inwardly extending oppositely disposed rear walls designated by the numeral 42. These walls are preferably flat, each having a substantially square opening 43 cut or formed therein. Such an opening is located adjacent the upper edge of each wall 42 to produce a narrow section or pintle 44. This pintle, like the pintle 39 on the spout 31, is used to hingeably connect the pouring spout 32 to the friction plug insert member 24. Each of the tongue members 29 disposed on the plug insert panel 25, may extend through its respective wall opening 43 and may then be looped around the pintle 44 in a suitable hinge connection.

A detent 45 is centrally disposed on the wall 36 of the pouring spouts 31, 32 adjacent the edge to produce a finger engaging means for raising the spout from its inoperative position (Fig. 1), to its operative and extended position (Fig. 3) for dispensing purposes. This is done by simply swinging the spout about its hinged connection.

An auxiliary friction plug closure member 46 (Figs. 1 and 4) comprises a dome like member having a panel 47 which merges into an annular depending inner wall 48 and thence into a substantially parallel and spaced annular upstanding outer wall 49. This upstanding wall frictionally engages the inner wall 26 of the plug insert. The upper edge of the wall 49 terminates in a hollow outwardly rolled rim or curl 52. The rolled rim 52 has a plurality of spaced flattened rim sections 53 (Fig. 4) which furnish a suitable clearance space 54 for the reception of a spoon handle or coin for easy removal of such a closure member.

Upon removal of the auxiliary plug closure member 46 either form of hinge spout 31, 32 may be raised from its retracted position (Fig. 1) to an extended position (Fig. 3) for conveniently

dispensing a desired quantity of the container contents. The pouring spout is then retracted into position within the plug insert member following such a dispensing operation and the closure member 46 may then be seated into the insert member 24 and thereby cover the dispensing spout to protect it and seal the container contents in a sanitary manner.

A dispenser and closure attachment 55, comprising a plug insert 24, a hinged pouring spout 31 or 32 and an auxiliary closure member 46 may be inserted into containers other than the friction plug cover type. Such an attachment can be conveniently inserted into any container end wall supplied with a suitable opening which may be initially closed and sealed by a usual type of friction plug closure, which closure may be easily removed for the reception of the dispenser attachment hereinbefore disclosed and thereafter serve as a useful container dispenser.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A dispenser and closure attachment for removable engagement with a dispensing opening in a wall of a container for dispensing liquids and other free flowing materials, comprising a friction plug insert member having a depressed panel surrounded by an annular wall, said panel having an elongated opening for effecting dispensing of the container contents, a pouring spout having a rounded front pouring lip and a rear stepped and curved wall, a pintle extending from opposite ends of the stepped curved wall of the pouring spout for hingeably connecting said spout to the insert panel by oppositely disposed integral tongue members extending outwardly from the panel and looped around the pintles, an arcuate ridge disposed in said panel and engageable against the inner surface of the stepped curved wall to direct the flow of container contents over said spout during a dispensing operation, a detent located on said rear curved wall for finger contact when raising the spout to a dispensing position, and an outer auxiliary friction plug closure having element for removable engagement with the annular wall of the friction insert member to cover and protect said pouring spout and seal the dispensing opening.

2. A sheet metal friction type container for storing and dispensing liquids and other free flowing materials, comprising a container having a friction ring, a main friction plug cover for insertion in said ring to close the container, said cover having an opening disposed adjacent an edge thereof surrounded by an annular wall, a friction plug insert member engageable within said cover opening and with the annular wall, said insert member having a panel and a dispensing opening formed therein for effecting dispensing of the container contents, a pouring spout hingedly connected to the panel, an arcuate ridge in the insert panel disposed to form a groove for the reception of the pouring spout when in a dispensing position, said ridge being adapted to direct the flow of the container contents to said spout, and an outer auxiliary friction plug closure element engageable with the friction insert mem-

ber to cover and protect the pouring spout when in a retracted non-pouring position and to seal the container contents.

3. A sheet metal friction top container for storing and dispensing liquids and other free flowing materials, comprising a container having a friction ring, a main friction plug cover for insertion in said ring to close the container, said cover having an opening disposed adjacent an edge thereof surrounded by an annular upturned wall, a friction plug insert member for closing said cover opening in engagement with the annular wall, a panel in said insert member and an opening in the panel for effecting dispensing of the container contents, a pouring spout having a rounded front pouring lip and a rear curved wall, pintles formed at opposite ends of the curved rear wall to hingedly secure said spout within looped tongue members struck from said panel, an arcuate ridge disposed in the panel to engage against the inner curved wall of the pouring spout when it is extended into pouring position to direct the flow of the container contents over said spout, and an outer auxiliary friction plug closure element for engagement with the friction insert member to cover and protect the pouring spout when in a retracted position within the plug insert member and to seal the container contents.

4. A sheet metal friction top container for storing and dispensing liquids and other free flowing materials, comprising a container having a friction ring, a main friction plug cover for insertion in said ring to close the container, said cover having an opening disposed adjacent one edge surrounded by an annular upturned wall, a friction plug insert member in said cover opening, and engageable with the annular wall, a panel in said insert member and an elongated dispensing opening in the panel for effecting dispensing of the container contents, a cylindrical wall pouring spout having a rounded and flared front pouring lip and a rear stepped and curved wall, said spout having rear flat walls extending from said stepped curved wall, an opening formed in each of said flat walls to set off a pintle between the opening and an edge of the flat wall, said pintles being adapted to be hingedly secured to the insert panel by looped tongue members struck and extending from said panel, an arcuate ridge located in said panel and engageable with the rear curved wall when the spout is in dispensing position to direct the flow of the container contents to said spout, a detent disposed centrally on said rear curved wall of said spout to facilitate raising the spout from an inopera-

tive position to a dispensing position, and an auxiliary friction plug closure having engagement with the friction insert member to cover and protect the pouring spout when in a retracted position within the plug insert member and to seal the container contents.

5. A sheet metal container for storing and dispensing liquids, comprising a tubular can body having a comparatively large opening in an end thereof, a friction plug for insertion in said opening to substantially close the container, said plug having a comparatively small opening adjacent an edge thereof defined by a friction seat wall, a cup-shaped friction plug for insertion in said friction seat wall for closing said small opening, said cup-shaped friction plug being of sufficient depth to completely house therewithin a pouring spout when the latter is in inoperative position, said cup-shaped friction plug having an upstanding wall and a bottom portion formed to provide a dispensing opening therein, said pouring spout being hingedly connected to said bottom portion for swinging movement into operative pouring position with its rear portion supported by said upstanding wall to effect dispensing of the container contents, said spout when in inoperative position being housed completely within said cup shaped friction plug, and a closure for said cup shaped friction plug to cover and protect said pouring spout when in inoperative position and to seal the container contents.

6. A sheet metal container for storing and dispensing liquids, comprising a tubular can body having a dispensing end provided with a pouring opening adjacent an edge thereof and defined by a friction seat wall, a cup shaped friction plug for insertion in said friction seat wall to close said pouring opening, said friction plug being of sufficient depth to completely house therewithin a pouring spout when in inoperative position, said cup shaped friction plug having an upstanding wall and a bottom portion formed to provide a dispensing opening therein, said pouring spout being hingedly connected to an inside wall of said friction plug and swingable into operative pouring position with its rear portion supported by said upstanding wall to effect dispensing of the container contents, said spout when in inoperative position being completely housed within said friction plug, and a closure for said friction plug to cover and protect said pouring spout when in inoperative position and to seal the container contents.

NELSON GEERTSEN.
